FIRE EXTINGUISHER

Filed Oct. 24, 1928

UNITED STATES PATENT OFFICE

ALBERT BLANKENHAGEN, OF AKRON, OHIO

FIRE EXTINGUISHER

Application filed October 24, 1928. Serial No. 314,605.

This invention relates to new and novel improvements in dispensing apparatus and while capable of application generally wherever it may be advantageously applied, it is particularly intended for use as a fire extinguisher in which connection it is illustrated in the drawing and hereinafter described.

Objects of the invention are to provide a dispensing apparatus of simple, durable construction, which may be provided at a low cost and which may be conveniently used and which will be extremely efficient in use.

A particular object is to provide a fire extinguisher of very simple construction, which may be loaded and permanently sealed whereby it may be kept indefinitely without impairing its efficiency, and, which may be manufactured at a low cost whereby it may be discarded after use.

Further objects are to provide a fire extinguisher including a permanently seated casing having a fire extinguishing agent enclosed in a collapsible tube mounted thereon and having two substances enclosed within the casing which when combined will produce a force which will bear against the outside of said collapsible tube and expel the contents thereof and to enclose one of said substances in a fragile container which may be broken by indenting the casing and to thereby provide means for generating a force within the casing without the use of valves, pins, punches or other apparatus which operate through an opening in the casing.

An additional object is to provide a fire extinguisher including a casing having a delivery opening or nozzle which is closed by a flat strip soldered to the casing whereby the strip may be forcibly removed to open the nozzle when the device is ready for use.

The above objects are accomplished and additional ends are attained by the novel construction, combination and arrangement of parts hereinafter described and illustrated in the accompanying drawing wherein I have shown one form of the invention, it being understood that the invention is capable of various adaptations and that changes and modifications may be made or resort had to

substitutions which come within the scope of the claim hereunto appended.

In the drawing like numerals of reference are used to denote like parts as the same may appear in any of the several views and in which:

Figure 1 is a side elevational view of a fire extinguisher constructed in accordance with this invention.

Figure 2 is a cross sectional view of same taken as indicated by the lines 2—2 of Figure 1.

Figure 3 is an elevational view of a fire extinguisher constructed in accordance with this invention,

Proceeding now to a detailed description of the invention with particular reference to the adaptation thereof illustrated in the drawing, the numeral 5 is used to denote the main body of the casing. The body 5 is cylindrical in form and is provided at one end thereof with a hemispherical end wall 6. The numeral 7 also denotes a portion of the casing. The portion 7 is similar in construction to the casing 5 and is likewise provided with a hemi-spherical end wall 8 which is similar to the end wall 6 on the portion 5. The numeral 9 denotes a member which is in the shape of a hollow truncated cone. A semi-spherical cup 10 is secured to the small end of the member 9. A hollow glass globe 11 is positioned in the cavity of the cup 10. The member 9 is provided at the large end thereof with an outwardly projecting, circumferentially extending flange 9a. The flange 9a is positioned against the axial edges of the casings 7 and 8. A band 12 is soldered or otherwise suitably secured around the joint thus formed to hold the several parts in assembled relation. A collapsible tube 13 which is preferably formed of lead or a similar ductile material is positioned within the cavity of the casing 5.

The tube 13 conforms in shape to the shape of the casing 5, being provided with a hemispherical end portion 14 which fits within the cavity of the end portion. The tube 13 is provided with an opening 15 which is preferably positioned through the end portion 14 so as to communicate with the similar

opening 16 in the portion 6 of the casing. A certain area of the tube 13 which extends entirely around the opening 15 is soldered or otherwise secured to the interior wall of the tube 15 whereby pressure exerted on the collapsible tube 13 will not escape between the outer walls of the tube 13 and the outer casing. A strip 17 of relatively thin sheet metal is soldered or otherwise secured to the 10 end portion 6 so as to entirely close the opening 16, the solder being kept in spaced relation to the opening 16. One end of the strip 17 is turned back upon itself to form a loop 17' in which is suitably mounted a ring 18 which may be engaged to forcibly pull the strip from the end 6 of the casing 5 thereby opening the nozzle 16. The portion 7 is provided with the cavity 19 which is adapted to contain a gas producing element. The 20 wall of the member 9 is provided with a plurality of openings 20.

A suitable quantity of carbonate of soda or other gas producing element is placed within the chamber 19 of the member 7 and 25 sulphuric acid or other gas producing substance is placed within the glass ball 7 which is adhesively secured in the seat 10. The member 7 is provided on the rounded end 8 thereof with a block 21 which is soldered or otherwise suitably secured thereon. The 30 arrangement is such that one side of the ball is in close spaced relation to the wall 8 of the portions 7 of the casing. The collapsible tube 13 is filled with carbon tetrachlorid or other 35 fire extinguishing liquid.

When it is necessary to use my improved fire extinguisher, the block 21 is brought into contact with some object with sufficient force to indent the wall 8 of the portion 7 of the 40 casing and break the glass ball 11. The acid within the ball unites with the gas producing element in the cavity 19, quickly forming an 45 expansible force therein. The ring 18 is then engaged and the strip 17 is forcibly torn from the end portion 6 of the casing 5. The 50 gas formed by uniting the gas producing elements passes through the openings 20 in the member 9 and compresses the collapsible tube 13 whereby the contents thereof will be forced outwardly through the openings 15 and 16.

Having thus illustrated my invention and described the same in detail what I claim as new and desire to secure by Letters Patent is:—

55 In a device of the class described, an enclosed casing, a perforated partition dividing said casing into a main chamber and a pressure generating chamber, a collapsible container in said main chamber said casing and 60 container having coinciding discharge openings, pressure producing substances in said pressure generating chamber, frangible container enclosing one of said substances, said frangible container supported by said partition in a position close to the wall of said 65

casing where it may be broken by forcing the wall of said casing against said frangible container and a flap removably soldered over the discharge opening in said casing.

In testimony whereof I have hereunto set 70 my hand.

ALBERT BLANKENHAGEN.
